BRACING SYSTEM FOR CONCRETE FORMS

Arthur W. Hecker, Shaker Heights, Ohio

Application February 28, 1933, Serial No. 659,011

4 Claims. (Cl. 25—131)

This invention relates in general to concrete construction, but has reference more particularly to a bracing system for the forms used in such construction.

5 In the erection of forms for casting or molding concrete structures, such as walls and the like, it is common practice to temporarily secure the forms in place and to take them down after the concrete has sufficiently set. Thus in building 10 walls, abutments and the like, such forms ordinarily consist of a series of planks or other concrete retaining members which are placed on edge one above the other so as to define a space of the required dimensions into which the concrete in 15 plastic state is then poured. It is important that such planks or equivalent forms should be readily removable when they have fulfilled their function without damage either to the concrete in the course of setting or to themselves, if such forms 20 are to be used over again.

An object of the invention, accordingly, is to provide a simple bracing system for thus securing in place forms of the kind described whether used in the construction of walls, floors, ceilings, side-walks, roadways or any structure adapted to be 25 made of concrete by pouring the same into a temporary form or mold. Another object of the invention is to provide improved clamping devices for temporarily securing in position the bracing 30 members of the aforesaid system. To the accomplishment of the foregoing and related ends, said invention, then, consists of the means hereinafter fully described and particularly pointed out in the claims.

35 The annexed drawing and the following description set forth in detail certain mechanism embodying the invention, such disclosed means constituting, however, but one of various mechanical forms in which the principle of the invention 40 may be used.

In said annexed drawing:

Fig. 1 is a fragmentary vertical transverse section through a composite form of the type ordinarily used in constructing concrete walls, etc., 45 my improved bracing system and clamping device being shown as in use to retain the parts of the form in proper place; Fig. 2 is a plan view of one of the clamping devices for securing the studs or vertical brace members in position; Figs. 3 and 50 4 are cross-sectional views of other rolled structural members which may be used instead of the rails as bracing members; and Fig. 5 is a fragmentary cross-sectional view, showing a modified form of spreader nut.

55 Referring more particularly to the drawing, I

and 2 represent wall forms which are spaced apart so as to define a space of the required dimensions into which the concrete in the plastic state is to be poured, these forms consisting of planks 3 or equivalent forms placed on edge one above the other. The forms are adapted to be maintained in properly spaced relation by means of nuts 4 of frusto-conical or other form which are threadedly secured to the ends of tie rods 5, the tie rod and nuts constituting what is usually referred to in the art as "spreaders."

The nuts 4, as clearly shown in Figs. 1 and 2, are provided with thin flat U-shaped members 6, which preferably extend centrally from and are formed integrally with the head of the nut. The 15 spreaders are so disposed that the members 6 extend through the joints between the edges of the planks 3, thereby avoiding substantially perforating or otherwise mutilating the planks as is common in many systems now in use. It will be 20 understood that the member 6, although of sufficient thickness to possess the strength required for the stresses to which it is subjected, is not so thick as to prevent the substantial abutment of the planks between which it passes, and that the 25 slight amount of "flash" formed by the cement oozing out between the planks can be readily scraped off.

In order to prevent the wall forms from bulging outwardly during the pouring of the concrete, I 30 provide studs or vertically extending bracing members, which, as shown in Figs. 1 and 2, are preferably in the form of T-rails 7. These T-rails extend upwardly between the arms of the U-shaped members 6 and are maintained in engagement 35 with the wall forms by means of clamping devices 8. The clamping devices 8 comprise flat U-shaped members, the arms 9 of which are provided with pins, studs or hooks 10 which are adapted to be entered in elongated openings 11 40 in the arms of members 6. After the members 6 and 8 are caused to engage in this manner, set screws 12 which are in threaded engagement with the member 8 may be adjusted to engage the head of the T-rail 7, thus holding these rails firmly in 45 engagement with the wall forms.

It will be particularly noted that by providing separable clamping devices 8, that the T-rails 7 may be properly positioned by simply placing them against the forms with a minimum of handling, whereas, if the devices 8 were integral with the members 6, the rails would have to be threaded through the vertically aligned openings thus formed, a procedure which would involve a considerable amount of labor. It will 50 55

also be noted that the use of set screws 12 permits a variety of sizes of rails to be used, as any loose play of the rails within the clamping devices may be readily taken up by these set screws.

Instead of bracing members in the form of T-rails, as described, I may without substantial modification of the clamping devices described, use rolled structural members, such as the H-beam 28 and the I-beam 30, illustrated in Figs. 3 and 4 respectively.

Instead of spreader nuts of frusto-conical form as described, I may employ hemispherical nuts 4' which, as shown in Fig. 5, are in threaded engagement with the tie-rod 5' and are provided with integral flat members 6', which are similar in all respects to the members 6.

It will be readily apparent that the use of a form bracing system such as I have described not only is labor saving in its erection and disassembling, but is also attended by a minimum degree of injury to the forms. After the concrete has set and the forms have been removed, the nuts 4 may be unscrewed from the tie-rods 5, the members 6 of such nuts serving as a means for manually rotating the nuts, thereby dispensing with the use of wrenches and other tools commonly employed for this purpose.

It will be seen that the bracing system consists of metallic members which may be easily handled and may be used almost indefinitely without sub-

stantial injury thereto or to the forms in conjunction with which they are used.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. As an element of a bracing system for concrete forms and the like, a spreader nut having a flat U-shaped member integrally secured to the head of said nut.

2. In a bracing system for concrete forms and the like, a spreader nut having a flat U-shaped member integral with the head of said nut, and a clamping device removably secured to said flat member.

3. In a bracing system for concrete forms and the like, a spreader nut having a flat U-shaped member extending from the head thereof, and a U-shaped clamping member removably secured to the arms of said first U-shaped member.

4. In a bracing system for concrete forms and the like, a spreader nut having a flat U-shaped member extending from the head thereof, a U-shaped clamping member removably secured to the arms of said first U-shaped member, and a set screw in threaded engagement with said removable clamping member.

ARTHUR W. HECKER.
